FIG. 7.

Inventor:

Arthur Jones,
 by *Arthur Jones*,
 of *Dear Middleton, N. H., U. S. A.*

UNITED STATES PATENT OFFICE.

ARTHUR JONES, OF COVENTRY, ENGLAND.

MECHANICAL INSTRUMENT FOR DIVIDING AND SPACING LINES OR DIMENSIONS AND TRANSFERRING SCALES FROM DRAWINGS.

1,258,574.

Specification of Letters Patent. Patented Mar. 5, 1918.

Application filed June 6, 1916. Serial No. 102,002.

To all whom it may concern:

Be it known that I, ARTHUR JONES, a subject of the King of Great Britain, residing at Coventry, in the county of Warwick, England, have invented a certain new or Improved Mechanical Instrument for Dividing and Spacing Lines or Dimensions and Transferring Scales from Drawings, of which the following is a specification.

10 This invention has for its object to provide a simple and accurate mechanical instrument for dividing and spacing lines or dimensions, and transferring scales from drawings. One of the chief features of this

15 invention is the ability to work to very small dimensions, such, for instance, as one tenth of a thousandth of an inch. The instrument is of the kind having a rule suitably graduated and a number of needles or

20 pointers connected together by trellis link, or lazy tongs mechanism.

In the accompanying drawings,

Figure 1 is a front elevation showing part of an instrument constructed in accordance with this invention. In order to show the instrument on a large scale, part has been broken away.

Fig. 2 is a view of the back plate showing the trellis mechanism and needles relatively arranged thereto.

Fig. 3 is a front view of part of the instrument with the needles closed up, while

Fig. 4 is a cross section on line 2-2 of Fig. 2.

35 Fig. 5 is a plan view of the left hand end, and

Fig. 6 is a similar view of the right hand end, while

Fig. 7 shows an edge view and Fig. 8 is 40 a front elevation of the cursor which may be used.

Like letters indicate like parts throughout the drawings.

The instrument comprises a front plate 45 A and a back plate B suitably spaced, as by means of spacing blocks A², and connected together by screws *a* or the like so as to leave an intermediate space. The front plate is graduated or divided in any suitable manner. For instance, at A⁴ a certain length, say 12 inches, may be divided and graduated in fractions of an inch. At A³ the same length may be divided into decimals or tenths of an inch. Sliding on the front 50 plate is a cursor C by which readings can be

accurately made. The cursor, as can be seen in Figs. 3 and 7 catches onto a dove-tailed edge c' of the rule. It is used for reading from the markings.

Located between the two plates is a series 60 of needles D, D¹, D², D³. The needle D¹ at the left hand end is a fixture, but the subsequent needles D are connected with one another by means of links E pivotally connected together in the form of a trellis. At each 65 pivotal connection between the ends of the links there is a sliding connection with the needles D. For instance, sliding on the exterior of each needle may be a sleeve or block E² pivoted to the trellis mechanism, the arrangement being such that when the needles are moved they travel through distances which are proportional to the position which each occupies in relation to the fixed needle D¹. For instance, if the extreme needle 70 D² is moved an inch, and if there are 10 needles the first one D³ moves one tenth of an inch, the second two tenths, the third three tenths, and so on.

Thus in reducing from one scale to a 80 smaller the extreme needles D¹ and D² are separated the amount of a certain dimension on the large scale, and if the required reduction is to be say, one half, the space between the first and the fifth movable needle is marked off on the reduced scale. If the reduction is to be three-fifths the sixth 85 movable needle is used, the distance between that and the fixed needle D¹ being exactly six-tenths of the distance between 90 the extreme needles D¹ and D². In transferring on to a larger scale the reverse process is followed.

It will be noticed that the points D⁴ of the needles are beveled off in two directions. 95 Figs. 1, 2 and 3 show the beveling in one direction, and the taper in the other direction is clear from Fig. 4.

Any suitable means may be employed for fixing the extreme needle D² in the required 100 position, as shown. In Figs. 2 and 6 there is shown attached to this needle a screw G which passes through a slot B² in the back plate and also through a clamping block H. When the nut G² is tightened up the needle 105 D² and the block H are drawn together and the needle D² is clamped to the back plate B. In conjunction with this block H there may be used a micrometer device for minutely adjusting the needle D². This con- 110

sists as shown in Fig. 6, of a second clamping block J with a clamping screw J^2 having a nut J^2 , and passing between the blocks H and J is a screw K carrying a knurled disk 5 or the head L. Above the periphery of this disk L may be a pointer M, which is visible in Fig. 4, but which has been omitted from Fig. 6 for the sake of clearness. If the screw K is provided with forty threads to the inch and if the periphery of the disk L is divided into twenty-five parts it is possible, in the well-known manner, to move the block H accurately through a distance of one-thousandth of an inch by first clamping 10 the block J to the base plate B and turning the disk L through one division marked on its edge. If the needle D^2 is in this manner moved through one thousandth of an inch the first movable needle D^3 next the needle 15 D^1 is moved through one-tenth of a thousandth of an inch.

It will be clear that when the needles are closed together as shown in Fig. 3 their points are separated a certain distance, 20 which for instance may be one tenth of an inch. In such a case when it is desired to measure distances of less than this amount there is provided a second fixed needle N shown in Figs. 1 and 2. This lies immediately behind the first movable needle D^3 when all the needles are closed up. When 25 therefore the extreme needle D^2 is moved through one thousandth of an inch the needles D^3 and N, which previously were superposed, will separate one tenth of a thousandth of an inch.

The lower points D^5 of the needles may be suitably shaped to suit screw threads to 30

enable the reading of these to be very easily ascertained.

What I claim as my invention and desire to secure by Letters Patent is:—

1. In combination, a slotted back plate, a graduated front plate attached thereto and spaced therefrom, trellis link mechanism between said plates and anchored at one end to one of said plates, a needle fixed relatively to said plates, movable indicating needles between said plates, a sliding connection between each of said needles and a pair of said trellis links, means passing through the slot in said back plate for locking the extreme needles, and a cursor sliding on said graduated front plate, substantially as set forth. 40

2. In combination a slotted back plate, a graduated front plate attached thereto and spaced therefrom, trellis link mechanism between said plates and anchored at one end to one of said plates, a needle fixed relatively to said plates, movable indicating needles between said plates, a sliding connection between each of said needles and a pair of said trellis links, means passing through the slot in said back plate for locking the extreme needles, and a cursor sliding on said graduated front plate and a micrometer adjustment between said locking means and said extreme needle, substantially as set forth. 45

In testimony whereof I have signed my name to this specification in the presence of two subscribing witnesses.

ARTHUR JONES.

Witnesses:

ALBERT SHACKLETON,
LEONARD JONES.
